DESIGN FOR AN EDGING

Solomon Elias, New York, N. Y.

Application March 11, 1949, Serial No. 1,360

Term of patent 14 years

(Cl. D92—1)

To all whom it may concern:

Be it known that I, Solomon Elias, a citizen of Bulgaria, residing at New York, in the county of New York and State of New York, have invented a new, original, and ornamental Design for an Edging, of which the following is a specification, reference being had to the accompanying drawing, forming a part thereof.

In the drawing:

Fig. 1 is a face view of an edging, showing my new design; and

Fig. 2 is a rear view of the same.

I claim:

The ornamental design for an edging, as shown.

SOLOMON ELIAS.
